UNITED STATES PATENT OFFICE.

JAMES G. AGNEW, OF ANNAPOLIS, MARYLAND, ASSIGNOR, BY MESNE ASSIGNMENTS,
TO R. P. KINZEY, TRUSTEE, OF UNITED STATES NAVAL ACADEMY, ANNAPOLIS,
MARYLAND.

DESIGN FOR A FINGER RING.

Application filed April 30, 1923. Serial No. 6,015. Term of patent 7 years.

To all whom it may concern:

Be it known that I, JAMES G. AGNEW, a citizen of the United States, residing at Annapolis, in the county of Anne Arundel and State of Maryland, have invented a new, original, and ornamental Design for Finger Rings, of which the following is a specification, reference being had to the accompanying drawing, forming a part thereof.

In the drawing, Fig. 1 is an elevation of one side and Fig. 2 is an elevation of the opposite side of a finger ring showing my new design.

I claim:

The ornamental design for a finger ring as shown.

In testimony whereof I have hereunto set my hand this 24 day of April, 1923.

JAMES G. AGNEW.
